MAGNETRON

Lloyd P. Smith, Ithaca, N. Y., assignor to Radio Corporation of America, a corporation of Delaware
Application April 24, 1948, Serial No. 23,045
41 Claims. (Cl. 315—39.57)

My invention relates to generators of high frequency radio waves using cavity resonators and more particularly to electron discharge devices such as magnetrons utilizing cavity resonators and to means for varying the generated frequency of such electron discharge devices.

This application is a continuation-in-part of my co-pending application, Serial No. 563,732, filed November 16, 1944, now abandoned. Said co-pending application was re-filed prior to abandonment as a continuation application Serial No. 285,627, filed May 2, 1952, now U. S. Patent No. 2,695,373, granted November 23, 1954.

It has become necessary to be able to vary the generated frequency over a limited frequency range of a magnetron or other ultra high frequency generator using cavity resonators as tank circuits. It is desirable to have the frequency change occur as a prescribed function of the time and with greater rapidity than is practical by mechanical tuning of the resonator. It is further desirable that the power output should be constant over the variable frequency range.

It is, therefore, an object of my invention to provide a high frequency generator utilizing a cavity resonator with means for varying or modulating the generated frequency.

Another object of my invention is to provide an electron discharge device utilizing cavity resonators and which can be frequency modulated.

More specifically it is an object of my invention to provide a magnetron utilizing cavity resonators and which can be frequency modulated by electronic means.

The novel features which I believe to be characteristic of my invention are set forth with particularity in the appended claims, but the invention itself will best be understood by reference to the following description taken in connection with the accompanying drawing in which Fig. 1 is a perspective view with parts broken away of one embodiment of my invention; Figs. 2, 3, and 4 are diagrams which help to explain the principles of my invention; Figs. 5 and 6 are equivalent circuits showing operation of apparatus made according to my invention; Fig. 7 is a graph illustrating the operation of a device made according to my invention; Fig. 8 is a plan view of a magnetron incorporating my invention with part of the shell cut away; Fig. 9 is a section on an enlarged scale taken along the line IX—IX of Fig. 11; Fig. 10 is a section taken along the line X—X of Fig. 8; Fig. 11 is a side view of the magnetron shown in Fig. 8 with part of the shell removed; and Fig. 12 is a section taken along the line XII—XII of Fig. 11.

The method and apparatus employing my invention can best be understood by reference to Fig. 1 which utilizes a cavity resonator, the resonant frequency of which can be changed by electronic means. In the device shown I provide an evacuated envelope 10 containing a rectangular cavity resonator 11 having dimensions X, Y, and Z. The cavity resonator is provided with oppositely disposed apertures 12 and 13 in opposite walls thereof through which an electron beam is directed. The electron beam is provided by means of an indirectly heated cathode 14 and can be controlled by a grid 15. An electrode 16 on the opposite side of the resonator and in the path of the electron beam may be used in place of or in combination with the grid 15. Transfer of energy to and from the cavity resonator 11 may be had by means of a coaxial line 17 coupled to the resonator by a loop 17' terminating

within the resonator. A constant magnetic field H is produced along the path of the beam of electrons by suitable means, such as a magnet having pole pieces 18 and 19. The magnet may be either a permanent magnet or an electromagnet. A control input circuit includes a transformer 20, and the voltage sources include grid biasing voltage source 21, cathode heater voltage source 22, voltage source 23 for applying a positive potential to the resonator 11 and voltage source 24 which may apply either a positive or negative voltage to the electrode 10, depending upon whether the electrode is to be used as a collector or reflector. Alternative arrangements for controlling the beam include a circuit having a transformer 25 for applying varying accelerating voltages to resonator 11 and a circuit including a transformer 25' connected to the electrode 16 for varying the voltage applied to this electrode when used as a control electrode to reflect electrons back into the resonator.

In order to set up an alternating electric field within the resonator some form of driving means is necessary. In the arrangement shown a cavity resonator magnetron 26 whose frequency is to be controlled is used as the driver. The magnetron is provided with a cathode 27 and radially directed vane elements 28, the inner edges of which provide anode segments. The wall of the envelope of the magnetron, which is a metallic envelope, and the vanes or slats 28 form cavity resonators between adjacent anode segments. This form of magnetron is well known. A magnetic field parallel to the cathode and between the cathode and the anode is provided by suitable means, not shown. The coaxial line 17 has a coupling loop 29 coupled to one of the magnetron resonators between adjacent anode segments. The coupling loop 17' of coaxial line 17 is oriented in the resonator 11 in a plane perpendicular to the beam path therein, so that high frequency electric and magnetic fields are generated in the resonator, with the electric field E in the direction indicated, inducing the desired mode of operation.

The constant magnetic field along the Z direction of the resonator serves two purposes. It keeps the electron beam together and it is by means of this magnetic field that electrons are made to move in such a way as to produce a large reactive effect in the interior of the cavity resonator. The cavity resonator is assumed to be excited at an angular frequency ω , with no electron beam present, for example by the magnetron 26 although it could be excited by other means. This frequency corresponds to the normal mode of oscillation for which the electric field is always parallel to the X direction of the resonator, that is, transverse to the direction of the electron beam.

When an electron has a linear velocity v in a direction at right angles to a uniform magnetic field H, it will describe a circular path. The time T_c required to traverse a complete circle is

$$T_c = \frac{2\pi m}{H|e|}$$

where m is the mass of the electron, |e| is the absolute value of its charge and H is the magnetic field intensity. Hence, this period of rotation is independent of both the electron's linear velocity and the radius of its circular path. The angular frequency of rotation is then

$$\omega_c = \frac{2\pi}{T_c} = \frac{H|e|}{m}$$

When an electron beam is made to traverse an oscillating cavity resonator, the resonant angular frequency ω of the particular mode of oscillation under consideration changes from ω_0 to $\omega_0 + \Delta\omega$. Where $\Delta\omega$ represents the shift in angular frequency caused by the passage of the beam through the resonator. The magnitude of the fre-

quency shift $\Delta\omega$ may be readily computed from developed formulas.

In a paper entitled "Frequency Modulation and Control by Electron Beams," by myself and Carl I. Shulman, published on pages 644-657 of Proceedings of the I. R. E., July 1947, it has been shown that for a rectangular cavity resonator, as shown in Fig. 1, the frequency shift is

$$\Delta\omega = -\frac{|I_0| |e| a^2}{2\epsilon m XYZ\omega_0^2} [f(u) + f(w)]$$

where $|I_0|$ is the total beam current, a is the transit angle of the electrons, ϵ is the dielectric constant within the resonator, XYZ is the volume of the resonator, ω_0 is the resonant angular frequency of the system before the electron beam is introduced,

$$f(u) = u \frac{(\pi^2 - u^2) - 2\pi^2 \sin u}{(\pi^2 - u^2)^2}$$

and $f(w)$ is the same function of

$$w, u = (1+k)a, w = (1-k)a, \pi = 3.1416, k = \frac{\omega_c}{\omega_0} = \frac{H|e|}{m\omega_0}$$

(see Equation 92, page 655 of said paper). When the transit angle a is not too small, the maximum frequency shift $\Delta\omega_{\max}$ occurs when $w = (1-k) a \approx 4$ radians. When the magnetic field is adjusted for maximum frequency shift the $\Delta\omega$ is proportional to the square of the transit angle a . For values of magnetic field considerably different from that necessary to produce maximum shift, $\Delta\omega$ can be shown to be approximately proportional to a .

In Fig. 7 there is shown the relationship of the change in frequency to the k ratio,

$$\frac{\omega_c}{\omega_0}$$

which is equal to

$$\frac{|e|H}{m\omega_0}$$

Fig. 7 gives an idea of the behavior and order of magnitude of the change in frequency $\Delta\omega$ per milliamper of beam current shown as a function of k for a 4000 megacycle rectangular resonator $Y=Z=5.3$ cm. and $X=.2$ cm., when the electrons in the beam have been accelerated through 100 volts. From the curve it will be seen that the frequency shift $\Delta\omega$ can be positive or negative depending upon whether k is less than or greater than one. Physically, as described above, this is due to the fact that when k is less than one the rotating electrons tend to fall behind the electric field, thus producing the effect of a lagging current, that is inductance. On the other hand, when k is greater than one, electrons get ahead of the field causing a capacitance effect and the frequency decreases.

The effectiveness of a given beam current in changing the frequency, that is in producing reactance, is the greatest when the magnetic field is adjusted to optimum conditions for the transit time used. Using the relationship $(1-k) a \approx 4$, given above, the two values of the ratio k for maximum frequency shift $\Delta\omega$ for the rectangular cavity resonator XYZ described, having a dimension $Z=5.3$ cm., a resonant frequency of 4000 megacycles and a 100 volt beam, are approximately .98 and 1.02, for positive and negative frequency shifts, respectively. Thus, Fig. 7 shows that for the rectangular resonator described ω_0 , a value of magnetic field such that the ratio k is substantially different from .98 and 1.02 causes the effect in the change of frequency to be hardly noticeable.

Thus, a means is provided for markedly changing the resonant frequency of a cavity resonator by electrons when the magnetic field is suitably adjusted. The frequency can be varied as an arbitrary function of the time by varying the beam current or the electron transit angle, or both, appropriately with the time.

As pointed out above, changing either the electron cur-

rent density or the electron transit angle will produce a corresponding change in the resonant frequency of the resonator 11. If a fixed voltage is applied to the resonator 11 and an alternating voltage applied to the grid 15 by means of the input 20, the current density is varied and hence the resonant frequency of resonator 11 is varied. If the voltage applied to the grid 15 is fixed and the accelerating voltage applied to the resonator varied by means of the input 25, the beam velocity and the 10 transit time and transit angle of the electrons through the resonator are varied, thus again varying the resonant frequency of the resonator 11. It may also be desirable to utilize the electrode 16 merely as a reflector, sending the electrons back to the resonator to be collected in the 15 resonator. In this case the alternating variable voltage may be applied to the reflector 16 by means of the input circuit 25'. It is, of course, understood in all these cases that magnetron 26 acts as the driver for the resonator to induce the alternating electric field in the proper mode 20 for bringing about the action desired, the change in frequency in the resonator 11 being reflected into the resonators of the magnetron 26 to vary its frequency. Thus, an electronic means is provided for frequency modulating a magnetron utilizing cavity resonators.

25 Thus, the tube shown in Fig. 1, composed of an appropriate resonator and beam supplying means and means for controlling the beam current or the transit time, constitutes a reactance tube which when closely coupled to a high frequency system can be used to vary the resonant 30 frequency of the system by introducing an almost pure inductive or capacitive reactance which can be varied with the time in any manner.

A better understanding of my invention may be had of the above by referring to Figs. 2, 3, 4, 5, and 6.

35 Consider a pair of parallel plates P across which an alternating potential difference is applied resulting in an electric field of amplitude E and angular frequency ω_0 between the plates, as shown in Fig. 4. A constant magnetic field H is provided in the direction shown. An electron is projected at uniform velocity into the field between the plates P along the dotted line ab parallel to the magnetic field. At time $t=0$ the electron will be at position 1, and at time Δt seconds later it will be at position 2, etc. At position 1 the electron has no velocity in the direction of E but on encountering the electric field E between positions 1 and 2 it will be accelerated in this direction. If the angular frequency ω_0 of the oscillating electric field E were equal to the angular rotation frequency,

$$\omega_c = \frac{He}{m}$$

each electron would remain in phase with the electric field and would be continuously accelerated so that it would receive more and more energy from the oscillating field and its motion would be a spiral of ever increasing radius. This condition would produce an electron current in phase with E at all positions, 1, 2, . . . , and would constitute a loading or resistive component of current. If the condenser plates P were to form part of a resonant circuit, by connecting an inductance between the plates, this "in phase component" would have no effect on the frequency, but would reduce the Q of the circuit.

65 The transit time of the electron through the condenser plates and the relative values of ω_0 and ω_c can be chosen so that the net electron current is not in the direction of E but is in quadrature to E so that it constitutes a purely reactive current. To see how this comes about, let ω_c be somewhat less than ω_0 . In this circumstance the electron will not complete one revolution during one complete cycle of the oscillating field. Consequently, it will lag behind E by a certain phase angle $\Delta\phi$, so that as the time goes on the electron lags more and more behind E . It will, however, continue to be accelerated until it lags

behind E by 90 degrees. The electron then still increases its lagging phase angle by $\Delta\phi$ on each revolution but the electron now is retarded by the oscillating field and loses energy. It is evident that for a given value of $\omega_c - \omega_0$, the time of flight of the electron between the condenser plates, can be adjusted so that the energy acquired from the field in the period during which acceleration took place is just given back to the field during the period of retardation and the net energy transfer from field to electron is zero. This situation is illustrated in Figs. 2, 3, and 4. When an electron enters the plates P at position 1, Fig. 4, it has no displacement from the median plane between the plates. This zero displacement is shown in Fig. 3. Also the transverse current at position 1 is zero as is shown in Fig. 2. At position 2, Fig. 4, the electron has acquired some circular motion and its displacement from the median plane is shown by the vector r_2 in Fig. 3. Since $\omega_c < \omega_0$ the electron lags behind E by the phase angle ϕ_2 when it reaches position 2. The transverse electron current in magnitude and phase relative to E is shown by the vector i_2 in Fig. 2. When the electron has reached position 3, its displacement is given by r_3 and the transverse current by i_3 . It is evident that at position 3 the magnitude of the current i_3 is greater than at position 2 as also is the lagging phase angle. At position 5, the electron has acquired its maximum displacement and the current i_5 due to it is 90° out of phase with E and is purely reactive. From this point on the electron is retarded and the current produced by it has a negative resistive component that is a component opposite to E. When electrons enter the condenser plates at all times as in a continuous beam, there will be electrons at all positions from 1 to 9 simultaneously and the total effective current will be the vector sum of the currents at each position. This vector sum is shown by I in Fig. 2. Thus the total effective current lags behind the field E by 90°. Thus E and I are related in phase exactly the same as the potential difference across an inductance and the current through it. If the condenser plates shown were in parallel with an inductance to form a resonant circuit with resonant frequency ω_0 , the passage of the beam of electrons through the condenser plates would increase the resonant frequency.

On the other hand, if $\omega_c > \omega_0$ then the currents i_2 , i_3 , etc. would lead E and $\omega_c - \omega_0$ would be so chosen that the total current would lead E by 90° giving rise to a decrease in the resonant frequency of the parallel circuit.

In effect, what the above means is that when the electrons lag the alternating electric field there is in effect an inductive reactance placed in parallel with the inductive reactance connected across the plates and the equivalent circuit is shown in Fig. 5. Inasmuch as this causes a reduction in the inductance reactance of the given frequency, the inductive and capacitive reactances do not provide resonance at this frequency. The frequency of the driving voltage must be raised to bring about resonance again. This causes the capacitive reactance to decrease and the inductive reactance to increase so that resonance is established at the higher frequency. Likewise, when the electrons are ahead of the electric field, the resultant effect is to place a capacitance in parallel with the capacitance of the plates, the equivalent circuit being shown in Fig. 6. This reduces the capacitive reactance of the resonator and in order to establish resonant conditions, the frequency must be lowered so that the inductive reactance decreases and the capacitive reactance increases. Thus, there is provided the means for varying the resonant frequency of the system above and below that which the system would have with no electron beam present. This is the action which takes place in a cavity resonator which is the equivalent of the resonant circuit discussed.

The effect of changing the transit time of the electrons through the plates can be seen from the following. Short-

ening the transit time for a given $\omega_c - \omega_0$ would have the same effect as that produced by shortening the plates. Thus, if the plates were terminated at position 7 in Fig. 4, the effective current between the plates would be given by the dotted vector in Fig. 2. In this case the inductive component of current has been decreased and a resistive component of current is present. Hence changes in the transit time can also be used to change the frequency of a resonant system composed of the condenser plates and a parallel inductance. On the other hand, varying the current density varies the length of the resultant vector I along the X axis since each of the components i_x and i_y is varied. Thus the inductive reactance is in effect varied and hence the frequency.

The frequency shift produced by projecting an electron beam along a magnetic field H and through an oscillating electric field E of frequency ω_0 between two parallel plates of length L and distance d apart has been shown, on pages 644-647 of the above-mentioned paper, to be approximately

$$\Delta\omega(\theta) = \frac{L^2}{8d^2} \frac{I_0}{V_0 C_0} \frac{\sin \theta - \theta}{\theta^2}$$

where $|I_0|$ is the total beam current, V_0 is the beam voltage, C_0 is the total equivalent capacitance of the system,

$$\theta = (\omega_c - \omega_0)\tau$$

$$\omega_c = \frac{H|e|}{m}$$

and τ is the electron transit time (see Equation 14, page 647 of said paper). For a given value of τ , $\Delta\omega(\theta)$ is a maximum when $\theta = (\omega_c - \omega_0)\tau = \pm\pi$ radians:

$$\Delta\omega(\pm\pi) = \pm \frac{L^2}{8d^2} \frac{|I_0|}{V_0} \frac{1}{\pi C_0}$$

Since

$$\tau = \frac{a}{\omega_0}$$

θ may be expressed

$$\left(\frac{\omega_c}{\omega_0} - 1 \right) a$$

or $(k-1)a$, where k is the ratio ω_c/ω_0 , and a is the transit angle of the electron in radians.

The same means for changing frequency can be incorporated in a high frequency generator to obtain a generator which can be internally frequency modulated. It is especially advantageous to apply the means explained above to frequency modulate a magnetron because arrangements can be made to use the same magnetic field used for the magnetron. Such a magnetron incorporating my invention and utilizing a multi-resonator system is shown in Figs. 8 to 12, inclusive.

In this arrangement an anode block 30 is provided with a central opening 31 extending therethrough. A plurality of anode segments 32 provided by radially directed vanes 32' mounted in the opening 31, as shown in Fig. 10, having a central space in which is axially mounted an indirectly heated cathode 33. It is obvious that, instead of the vane type anode arrangement, the block could be provided with radial slots for obtaining anode segments, or other forms of spaces between anode segments could be provided. The spaces or slots provide cavity resonators 32'' which in the form shown are provided between adjacent anode vanes 32' by the vanes and the wall of the opening 31 in the anode block. If desired, the various anode vanes may be strapped together at one or both ends by means of conducting ring members 70 and 71, the rings being conductively connected to alternate vanes, as shown in Figs. 9 and 10, to facilitate operation in the desired mode.

Magnetic inserts 34 and 35 are carried by bridge members 36 and 37 which are mounted on the anode block 30 in insulating relationship to the block by means of bolts 38, nuts 39, insulating sleeves 40 and 40', 41 and

41' and 42 and 42'. The cathode 33 is supported by the magnetic insert 34. One lead 43 of the cathode heater 33' is connected to the insert 34 which is in electrical contact with the cathode 33 and bridge member 36, and the other lead 43' extends through an eyelet and is sealed through a header 45 forming part of the envelope by means of a glass bead and seal 43''. The bridge member 36 is electrically connected to a lead 44 which extends through and is sealed in the header 45 by means of an insulating tube 44'. The anode block 30 may be supported from the header 45 by means of the supports 46 and 47. An output coupling loop 50 disposed in one of the cavity resonators terminates in a coaxial line 51-52 sealed at its outer end by means of an insulating bead 53. As shown in Figs. 11 and 12, the anode block 30, the envelope 45-55 and the outer conductor of coaxial line 51-52 are in contact, and hence, are maintained at the same potential. A magnet having poles 56 and 56' cooperates with the magnetic inserts 34 and 35 to provide the usual magnetic field in the cathode space and also provide a magnetic field in the resonators parallel to the cathode 33 and the resonator walls.

In accordance with my invention, I provide one or more electron guns each comprising an indirectly heated cathode sleeve 60 supported by the insert 35 by means of an insulating collar 61. The leads 62 and 63 for each cathode heater 60' extend through and are sealed by an insulating tubular member 64 in the header 45. One lead 63 is electrically connected to the sleeve 60. A grid 66 is insulatingly mounted on the end of each cathode sleeve by means of an insulating collar 66' and a flanged sleeve 66'' having a lead 65 sealed through an insulating tubular member 65' in the header. Each electron gun is located adjacent one side of a cavity resonator 32'' in position to project a modulating electron beam through the portion of the resonator adjacent the cathode in a direction parallel to the magnetic field. An anode electrode 67 is provided adjacent the opposite side of the cavity resonator in the path of the modulating beam to serve as a collector therefor. The collector 67 is provided with a lead 68 sealed through an insulating tubular member 68'.

The operation of the magnetron of Figs. 8-12 is similar to that of Fig. 1, the principal difference being that the cavity resonators 32'' of the magnetron are excited by the space charge rotating in the cathode space while the cavity resonator 11 of Fig. 1 is excited by an external source 26 coupled thereto. The cathode sleeve 60 and grid 66 may be biased negatively with respect to the anode block 30 by connecting the leads 63 and 65 through suitable biasing sources 72 and 73 to the tube envelope, as shown in Fig. 11.

To frequency modulate the magnetron a signal may be applied to the control grid 66 by an input circuit including a transformer 74. As an alternative, however, the grid may be eliminated and the velocity of the electrons controlled by applying an alternating voltage between the anode block 30 and cathode 60 as in Fig. 1.

For a given tapered cavity, as shown in Figs. 8-12, the optimum location of the modulating beams radially along the resonator for maximum frequency shift will lie as near to the point of maximum electric field and minimum distance between the vanes, at their inner edges, as is consistent with substantial beam diameter, maximum beam current. The modulating beams B have been illustrated in positions just outside the strapping ring 70. If desired, the strapping rings may be made smaller or larger, or even eliminated, and the beams located closer to the inner edges of the vanes.

Electrode 67 may be used as a reflector like electrode 16 of Fig. 1 in which case the electrons will be repelled back through the resonator and collected by the anode vanes, thus varying the transit time of the electrons through the resonator. As in Fig. 1, the electrode 67

may be biased positively or negatively with respect to the cathode 60 by connecting lead 68 to a biasing voltage source 75, as shown in Fig. 12. A modulating signal voltage may be superimposed upon the bias voltage of electrode 67, by means of an input circuit including a transformer 76 in series with the source 75 and the cathode lead 63.

Although two modulating beams have been shown in Figs. 8-12, it is obvious that the modulating beams could be projected through only one or more than two resonators. The cylindrical beams shown could be replaced by an annular beam and collector. These are all equivalents of the arrangement shown.

The invention may be applied to magnetrons having any number of anode segments and resonators.

While I have indicated the preferred embodiments of my invention of which I am now aware and have also indicated only two specific applications for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

The embodiment of my invention illustrated in Fig. 1 is claimed in my above-mentioned Patent No. 2,695,373.

What is claimed is:

1. An electron discharge device having an anode comprising a plurality of spaced anode elements defining a central space, adjacent elements being connected by hollow resonators, a cathode arranged adjacent said anode elements to supply electrons within said central space for exciting said resonators to produce a transverse alternating electric field within said resonators, means adjacent said anode for providing a magnetic field within said space and resonators and extending substantially normal to said electric field, and means for directing a stream of electrons within a hollow resonator in a direction substantially parallel to the magnetic field to vary the impedance of said resonator.

2. An electron discharge device having an anode comprising a plurality of spaced anode elements defining a central space, adjacent elements being connected by hollow resonators, a cathode arranged adjacent said anode elements to supply electrons within said central space for exciting said resonators to produce a transverse alternating electric field within said resonators, means adjacent said anode for providing a magnetic field within said space and resonators extending substantially normal to said electric field, means for directing a stream of electrons within a hollow resonator in a direction substantially parallel to the magnetic field, and control means for varying the flow of the electrons in said stream, whereby the impedance of said resonator is varied.

3. An electron discharge device having an anode comprising a plurality of spaced parallel anode elements defining a central space, adjacent elements connected by hollow resonators, a cathode arranged adjacent said anode elements to supply electrons within said central space for exciting said resonators to produce a transverse alternating electric field therein, means adjacent said anode for providing a magnetic field within said space and resonators extending substantially parallel to said elements and normal to said electric field, means adjacent said anode for directing a stream of electrons through a hollow resonator in a direction substantially parallel to the magnetic field, and means for controlling the flow of said stream comprising a reflector electrode oppositely disposed to the last named means.

4. An electron discharge device having an anode comprising a plurality of spaced anode elements defining a central space and lying parallel to a central axis, cavity resonators connected between adjacent elements, an elongated cathode within said central space and lying along the central axis of said anode elements for supply-

ing electrons within said space for exciting said resonators to produce an alternating electric field therein, means adjacent said anode for providing a magnetic field within said space and resonators extending substantially parallel to said cathode and elements, means for directing a stream of electrons within a resonator in a direction substantially parallel to said magnetic field, and a control grid in the path of said stream for varying said stream of electrons during operation of said device for varying the impedance of said resonator.

5. An electron discharge device having an anode comprising a plurality of spaced anode elements defining a central space and lying parallel to a central axis, cavity resonators connected between adjacent elements, an elongated cathode within said central space for supplying electrons within said space and lying along said axis, means adjacent said anode for providing a magnetic field within said central space and resonators extending parallel to said cathode and elements, means for directing a stream of electrons within a resonator in a direction substantially parallel to the magnetic field, a control grid in the path of said stream of electrons for varying said stream during operation of said device, whereby the impedance of said resonator may be varied, and a collector electrode oppositely disposed to the last named means.

6. An electron discharge device having an anode comprising a plurality of spaced anode elements defining a central space and lying parallel to a central axis, cavity resonators having a resonant frequency and connected between adjacent elements and each enclosing a space, a cathode arranged adjacent said anode elements to supply electrons within said central space for exciting said resonators to produce a transverse alternating electric field of said resonant frequency within said resonators, means adjacent said anode for providing a magnetic field within said central space and the spaces enclosed by said resonators and extending normal to the alternating electric field within said resonators, and means for varying the frequency of oscillation of said resonators comprising means for directing a stream of electrons within a space confined by one of said resonators in a direction substantially parallel to said magnetic field and normal to said electric field, an electrode oppositely disposed to the last named means, and other means for controlling said stream of electrons.

7. An electron discharge device having an electrode assembly including an anode block having a plurality of spaced anode segments extending radially toward and defining a central space, the spaces between adjacent segments providing hollow cavity resonators of predetermined resonant frequency, an elongated cathode for supplying electrons within said central space for exciting said resonators to produce transverse alternating electric fields at said frequency within said resonators, means supporting said cathode in said central space in insulating relationship with respect to said anode block, means adjacent said electrode assembly for providing a magnetic field within said central space and said resonators normal to said electric fields, and means for varying the resonant frequency of said resonators comprising means for directing a stream of electrons within a resonator in a direction substantially parallel to the magnetic field.

8. An electron discharge device having an electrode assembly including an anode block having a plurality of spaced anode segments extending radially toward and defining a central space, the spaces between adjacent anode segments providing hollow cavity resonators, a cathode adjacent said anode segments for supplying electrons within said central space for exciting said resonators to produce alternating electric fields within said resonators and means insulatingly supporting said cathode with respect to said anode block and including a bridging member extending across said resonators and said central space, means adjacent said electrode assembly for providing a magnetic field within said central space and said resonators

normal to said electric fields, and a second cathode adjacent said anode block for directing a stream of electrons into a resonator in a direction substantially parallel to said magnetic field.

5. An electron discharge device having an electrode assembly including an anode block having a plurality of spaced anode segments extending radially toward and defining a central space, the spaces between adjacent anode segments providing hollow cavity resonators, a cathode adjacent said anode segments for supplying electrons within said central space for exciting said resonators to provide alternating electric fields within said resonators, means adjacent said electrode assembly for providing a magnetic field within said central space and within said resonators normal to said electric fields, said means including magnetic inserts on opposite sides of said anode block, said cathode being supported by one of said inserts, a second cathode adjacent said anode block for directing a stream of electrons into a resonator in a direction substantially parallel to said magnetic field, said second cathode being supported by one of said inserts, and means for controlling the stream of electrons from said second cathode, whereby the frequency of operation of said electron discharge device may be varied.

10. An electron discharge device having an anode comprising a series of hollow resonators opening into a cathode space, means adjacent said anode for establishing a constant magnetic field within said space and resonators, a cathode arranged adjacent said anode to supply electrons within said space for exciting said resonators to produce a transverse alternating electric field within said resonators, and means for directing a stream of electrons through one of said resonators.

11. An electron discharge device having an anode comprising a plurality of spaced parallel anode elements defining a central space, adjacent elements being connected by hollow resonators, means adjacent said anode for providing a magnetic field within said space and resonators parallel to said anode elements, cathode means adjacent said anode elements for supplying electrons within said central space, said anode and cathode means being adapted to be maintained at positive and negative direct current potentials, respectively, for exciting said resonators to produce transverse alternating electric fields therein, and means for directing a stream of electrons within a resonator in a direction having a substantial component parallel to said magnetic field and normal to said electric fields.

12. A magnetron having an anode comprising a plurality of spaced parallel anode segments surrounding a central space, adjacent segments being connected by hollow resonators, said segments and resonators having capacitance and inductance determining their normal resonant frequency, means adjacent said anode for producing a magnetic field within said central space and the portions of said resonators adjacent said central space in a direction substantially parallel to said anode segments, a cathode arranged adjacent said anode elements to supply electrons within said central space for exciting said resonators to produce a transverse alternating electric field within said resonators, and means for varying the resonant frequency of said resonators comprising means for directing a stream of electrons within one of said resonator portions adjacent said central space in a direction substantially parallel to the magnetic field.

13. A magnetron comprising at least one hollow resonator having inductance and capacitance and a normal mode of oscillation at a resonant angular frequency determined by said inductance and capacitance, means including a cathode adjacent said resonator for establishing an oscillating electric field of said frequency and mode between two opposite walls of said resonator, means adjacent said resonator for providing a constant magnetic field within said resonator in a direction substantially parallel to said opposite walls, and means for directing a stream of electrons between said opposite walls in a

direction substantially parallel to said magnetic field, the field strength of said magnetic field being slightly different from

$$\frac{\omega m}{e}$$

where ω is said resonant angular frequency, and m and e are the mass and electrical charge of an electron, respectively, whereby the electrons traversing the crossed electric and magnetic fields within said resonator will execute spiral paths slightly out of phase with the oscillating electric field, producing a reactive effect which changes the resonant angular frequency of the magnetron.

14. A magnetron according to claim 13, including control means for varying the flow of said electrons in said stream.

15. A magnetron according to claim 14, wherein said control means comprises a grid electrode disposed in the path of said stream of electrons.

16. A magnetron according to claim 13, including a reflector electrode oppositely disposed to said means for directing a stream of electrons between said opposite walls.

17. A magnetron having a cathode, an anode structure adjacent said cathode and comprising a series of cavity resonators open toward said cathode, and means for varying the impedance of said resonators comprising means for directing a stream of electrons through at least one of said resonators in the region near the cathode where a strong oscillating electric field is generated during the operation of the magnetron.

18. A magnetron comprising at least one hollow resonator having inductance and capacitance and a normal mode of oscillation at a resonant angular frequency determined by said inductance and capacitance, means including a cathode adjacent said resonator for establishing an oscillating electric field of said frequency and mode between two opposite walls of said resonator, means adjacent said resonator for providing a constant magnetic field within said resonator in a direction substantially parallel to said opposite walls, and means adjacent said resonator for directing a beam of electrons through said resonator between said opposite walls in a direction substantially parallel to said magnetic field, the intensity H of said magnetic field and the transit time τ of the electrons through said resonator being so related to said resonant angular frequency ω_0 that $(He/m - \omega_0)\tau$ is substantially equal to π radians, where e and m are the charge and mass, respectively, of an electron and π is 3.1416, whereby during operation of said magnetron the electrons of said beam execute spiral paths through said resonator out of phase with said oscillating field and thus produce a maximum reactive effect for a given beam current upon said resonator to change the resonant angular frequency of the magnetron.

19. An electron-discharge device comprising: a cathode; an anode structure, spaced from said cathode, and including a cavity resonator; means, supported adjacent said cathode and said anode structure, for establishing a magnetic field through said cavity resonator in a direction transverse to the electron-path between said cathode and said anode structure; a source of electrons supported adjacent said cavity resonator; and means, intermediate said source of electrons and said cavity resonator, for directing the electrons emitted by said source into said cavity resonator along a path within and substantially parallel to said magnetic field, whereby said device may be tuned to a frequency other than its natural resonant frequency.

20. An electrode-discharge device comprising: a cathode; an anode structure, spaced from said cathode, and including a plurality of anode members; each pair of adjacent anode members, together with that portion of said anode structure lying therebetween, defining a cavity

resonator; means supported adjacent said cathode and said anode structure, for establishing a magnetic field through said cavity resonators; a source of electrons supported adjacent said cavity resonators, and means, intermediate said source of electrons and said cavity resonators for directing the electrons emitted by said source into said cavity resonators along a path within and substantially parallel to said magnetic field, whereby said device may be tuned to a frequency other than its natural resonant frequency.

21. An electron-discharge device comprising: a cathode; an anode structure, spaced from said cathode, and including a cavity resonator; means, supported adjacent said cathode and said anode structure, for establishing

22. A magnetic field in a direction transversely of the electron-path between said cathode and said anode structure; said magnetic field having a portion thereof extending through said cavity resonator; a source of electrons, supported adjacent said cavity resonator, and adapted to have a

23. voltage established between itself and said anode structure for directing the electrons emitted thereby into said cavity resonator along a path within and substantially parallel to said magnetic field, whereby said device may be tuned to a frequency other than its natural resonant frequency.

24. A magnetic field in a direction transversely of the electron-path between said cathode and said anode structure; said magnetic field having a portion thereof extending through said cavity resonator; a source of electrons, supported adjacent said cavity resonator, and adapted to have a voltage established between itself and said anode structure for controlling the density of the electron-flow between said source and said anode structure.

25. An electron-discharge device comprising: a cathode; an anode structure, spaced from said cathode, and including a plurality of anode members; each pair of adjacent anode members, together with that portion of

26. said anode structure lying therebetween, defining a cavity resonator; means, supported adjacent said cathode and said anode structure, for establishing a magnetic field in a direction transversely of the electron-path between said cathode and said anode structure; said magnetic field having a portion thereof extending through said cavity resonators; a source of electrons, supported adjacent said cavity resonators, and adapted to have a voltage established between itself and said anode structure for directing the electrons emitted thereby into said cavity resonators along a path within and substantially parallel to said magnetic field, whereby said device may be tuned to a frequency other than its natural resonant frequency;

27. and means, supported intermediate said source of electrons and said anode structure, for controlling the density of the electron-flow between said source and said anode structure.

28. A magnetron having a cathode, an anode structure adjacent said cathode and comprising a series of cavity resonators open toward said cathode, and means for varying the impedance of said resonators comprising cathode means separate from said cathode for supplying electrons within one of said resonators.

29. A magnetron according to claim 23, further including means for varying the flow of said electrons.

30. A magnetron according to claim 23, further including a control grid adjacent said cathode means.

31. A magnetron according to claim 23, further including a reflector electrode oppositely disposed to said cathode means.

32. A magnetron according to claim 23, further including means connected between said cathode means and said anode structure for applying a variable voltage therebetween.

33. An electron-discharge device comprising a cathode, an anode structure spaced from said cathode and including a pair of anode faces interconnected by a cavity resonator open at both ends, means adjacent said cathode for maintaining a magnetic field through said cavity resonator in a direction extending between said open ends, a thermionic electron-emitting electrode facing one of said open ends, and an electron reflecting electrode

34. facing the other of said open ends.

29. An electron discharge device comprising a cathode, an anode structure spaced from said cathode and including a pair of anode faces interconnected by a cavity resonator open at both ends, means adjacent said cathode for maintaining a magnetic field through said cavity resonator in a direction extending between said open ends, and a pair of electrodes, at least one of which is a thermionic electron-emitting electrode, facing said open ends.

30. A frequency modulating oscillator system including an electron discharge device comprising a cathode, an anode structure spaced from said cathode and including a pair of anode faces interconnected by a cavity resonator open at both ends, means adjacent said cathode for maintaining a magnetic field through said cavity in a direction extending between said open ends, a pair of electrodes, at least one of which is a thermionic electron-emitting electrode, facing said open ends, means, connected intermediate said electrodes and said anode structure, for biasing each of said electrodes negatively with respect to said anode structure, and means, connected in series with said biasing means, for superimposing a modulating signal voltage on at least one of said electrodes.

31. An electron discharge device comprising a cathode, an anode structure spaced from said cathode and including a pair of anode faces interconnected by a cavity resonator open at both ends, means adjacent said cathode for maintaining a magnetic field through said cavity resonator in a direction extending between said open ends, a thermionic electron-emitting electrode facing one of said open ends and an electron reflecting electrode facing the other of said open ends, said electron emitting and reflecting electrodes being electrically isolated from said cathode.

32. An electron discharge device comprising a cathode, an anode structure spaced from said cathode and including a pair of anode faces interconnected by a cavity resonator open at both ends, means adjacent said cathode for maintaining a magnetic field through said cavity resonator in a direction extending between said open ends, and a pair of electrodes, at least one of which is a thermionic electron-emitting electrode, facing said open ends, said electrodes being electrically isolated from said cathode.

33. A tunable electron-discharge device comprising: a cathode; an anode structure spaced from said cathode, and incorporating a cavity resonator in which radio-frequency oscillations are adapted to be generated; means adjacent said cavity resonator for establishing a magnetic field therethrough; means, cooperable with the electric-field component of said radio-frequency oscillations, and with said magnetic field, for setting up a space charge in said cavity resonator; and means, coupled between said cavity resonator and said last-named means, for varying the density of said space charge.

34. An electron-discharge device comprising a cathode, an anode structure spaced from said cathode and including a pair of anode faces interconnected by a cavity resonator open at both ends, means for maintaining a magnetic field through said cavity in a direction extending between said open ends, a source of electrons facing one of said open ends, and an electron-reflecting electrode facing the other of said open ends.

35. An electron-discharge device comprising a cathode, an anode structure spaced from said cathode and including a pair of anode faces interconnected by a cavity resonator open at both ends, means for maintaining a magnetic field through said cavity in a direction extending between said open ends, and a pair of electrodes facing said open ends, at least one of said electrodes being electron emissive during operation.

36. The method of loading a high frequency generator having a cathode and an anode cavity resonator, comprising the steps of providing a constant magnetic field extending through said resonator, projecting an electron beam through said resonator along said magnetic field,

adjusting the intensity of said magnetic field as a function of the operating frequency of said generator to provide maximum loading and negligible reactive effect by said electron beam, and varying the energy-absorbing ability of said beam to vary the loading of said generator.

37. The method of loading a high frequency magnetron generator having a central cathode and a plurality of anode cavity resonators surrounding said cathode, comprising the steps of projecting an electron beam through one of said resonators in a direction parallel to said cathode, providing a magnetic field extending parallel to said beam and through said one of said resonators, connecting said generator to a source of operating potentials to provide high frequency oscillations therefrom, adjusting the intensity of that portion of said magnetic field which extends through said resonators to a value at which the electron rotation frequency thereof is substantially equal to the angular frequency of said oscillations, and varying the conductance of said beam to vary the loading of said generator.

20 of said generator.

38. A magnetron comprising a first electron-emissive cathode and an anode disposed adjacent said cathode, means connected with and for applying operating potentials to said anode and cathode and thereby obtaining electron flow on paths from the cathode toward said anode to generate microwave oscillations on said anode, a second electron-emissive cathode opposed to another part of said anode for also directing electrons to the anode but to said other part thereof on paths other than the aforesaid paths of electron flow, and for thereby modifying the said microwave oscillations, and means in the path of and for controlling the electrons emitted from said second cathode.

25

30

39. An electron-discharge device comprising: a cathode; an anode, incorporating a cavity resonator, spaced from said cathode; means, adjacent said anode, for establishing a unidirectional magnetic field in said cavity resonator; and means, incorporated in said device, for projecting a stream of electrons into said cavity resonator to control the resonant frequency of said device.

40. An electron-discharge device comprising: a cathode; an anode, incorporating a cavity resonator, spaced from said cathode; means, adjacent said anode, for establishing a unidirectional magnetic field in said cavity resonator; means, incorporated in said device, for projecting a stream of electrons into said cavity resonator to control the resonant frequency of said device; and means, coupled to said last-named means, for varying the density of said stream of electrons to frequency modulate said device.

50 41. An electron-discharge device comprising: a cathode; an anode spaced from said cathode; said anode including a pair of anode arms which, together with that portion of said anode lying therebetween, defines a cavity resonator; means, adjacent said anode, for establishing a magnetic field through said cavity resonator in a direction transverse to the discharge path between said cathode and said anode; and a source of electrons, communicating with said cavity resonator and adapted to project electrons therein, for altering the resonant frequency thereof.
